Otto E. Trautmann, Irondequoit, N. Y., assignor to Bausch & Lomb Optical Company, Rochester, N. Y., a corporation of New York

Application March 27, 1937, Serial No. 68,446

Term of patent 14 years

To all whom it may concern:

Be it known that I, Otto E. Trautmann, a citizen of the United States and a resident of the town of Irondequoit, county of Monroe, and State of New York, have invented a new, original, and ornamental Design for an Opera Glass or Similar Article, of which the following is a specification, reference being had to the accompanying drawing, forming a part thereof.

Fig. 1 is a front view of an opera glass or similar article, showing my new design.

Fig. 2 is an end view thereof.

Fig. 3 is a top plan view of same.

Fig. 4 is a bottom plan view of same.

I claim:

The ornamental design for an opera glass or similar article, substantially as shown.

OTTO E. TRAUTMANN.
